His Attorney.

UNITED STATES PATENT OFFICE

2,570,769

ELECTRIC CIRCUIT INTERRUPTER

Thellwell R. Coggeshall, Bala Cynwyd, Pa., assignor to General Electric Company, a corporation of New York

Application November 10, 1948, Serial No. 59,296

2 Claims. (Cl. 200—150)

1

This invention relates to high voltage electric apparatus in which use is made of long hollow ceramic or other brittle insulators and more particularly to supporting means for the insulating structure of high voltage interrupters wherein the interrupting contacts are disposed within a relatively long tubular insulating housing structure which comprises an inner insulating tubular casing constructed of fiber or other suitable organic insulating material surrounded by an outer weather protecting tubular shell of inorganic or ceramic material.

In Patent 2,162,588—Prince, granted June 12, 1939, and assigned to the assignee of this application, there is disclosed a circuit interrupter wherein the contact structure is mounted within a housing structure comprising an inner tubular insulating member surrounded by outer tubular members constructed of relatively heavy and brittle ceramic material. In the Prince patent the inner insulating tubular member is rigidly secured at either end to a supporting chamber or carriage respectively and the outer ceramic insulating shell is constructed in two sections each of which is supported at one end to the chamber or carriage only in a cantilever fashion. The voltage rating for a circuit breaker manufactured in accordance with the teaching of this Prince patent is necessarily limited because the relatively heavy weight and the brittle nature of the ceramic outer shell impose a limitation on the length of shell section which can be supported by a cantilever arrangement. Thus, in order to make possible an increase in the voltage rating of a circuit interrupter such as that disclosed in the Prince patent, it is vital to provide suitable supporting means for the weather protecting outer shell which makes possible the use of a longer shell and hence a greater number of serially-arranged interrupting contacts.

One object of my invention is to provide an improved construction for supporting relatively long and heavy insulating shells concentrically about an inner insulating casing so as to make possible an increase in the voltage rating of high voltage electrical apparatus.

Another object of my invention is the provision of an improved construction for supporting a substantially horizontally disposed outer ceramic shell of a circuit interrupter in a flexible fashion so that destructive shocks due to the operation of the contacts within the casing, as well as external shocks due to ground tremors, for example, are not transmitted to the outer relatively brittle shell.

2

Still another object of my invention is to provide an improved circuit breaker construction wherein the weight of an outer protective relatively heavy insulating shell is taken by flexible means disposed between an inner insulating non-brittle tubular casing and the brittle shell so as to insulate the shell from radial or longitudinal shocks and wherein means are provided for retaining oil or other suitable insulating liquid within the space between the inner casing and outer insulating shell.

For protecting the outer shell from radial shocks due to the operation of the contacts within the inner tubular member, a plurality of resilient or flexible annular spacers are disposed at intervals longitudinally along the exterior surface of the inner tubular casing for supporting the outer shell. For protecting the shell against longitudinal shocks, annular resilient spacers are disposed between the adjacent ends of the shell sections. For the purpose of retaining insulating liquid within the space between the concentrically disposed insulating casing and the outer ceramic shell, adjacent ends of the shell sections are suitably interconnected by flexible sealing means. Furthermore, means are provided for permitting the distribution of liquid longitudinally along the space between the inner tubular casing and the outer shell members disposed thereon.

My invention will be better understood with reference to the drawings in which Fig. 1 is a side view partly in section of a circuit interrupter embodying my invention and in which Fig. 2 is an enlarged sectional view of a portion of the interrupter shown in Fig. 1.

While I have illustrated my invention in connection with a circuit interrupter wherein a plurality of pairs of serially arranged contacts are simultaneously operated by a common actuating member, and wherein a piston is utilized to force a blast of liquid between each pair of contacts during the circuit interrupting operation, it will be understood that my invention is not limited to such an interrupter and that it is applicable to other types of comparable high voltage electrical apparatus as well.

In Fig. 1 the horizontal interrupter unit is supported by suitable insulating vertical columns 1 and 2. The insulating column 1 is hollow and contains certain portions of the contact operating mechanism which, for simplicity, have been omitted from the drawing as these form no part of my invention. Disposed on the supporting column 1 is the linkage mechanism housing gen-

generally indicated at 3, and the terminal cap generally indicated at 4 is mounted at the opposite end on the insulating supporting column 2. The structure housing the contacts is generally indicated by the numeral 5 and is supported at 5 either end by the housing 3 and the terminal cap 4.

While the particular construction of the contacts and the operating mechanism therefor forms no part of the present invention, a brief description thereof is here included for completeness. The movable contacts 6, 7, 8, 9, and 10 are mounted upon and movable with the common connecting rod 11 and cooperate respectively with the fixed contacts 12, 13, 14, 15, and 16 all of which are shown by dotted lines in Fig. 1. It will be understood, of course, that suitable connecting means would be provided for insulating movable contacts 6 and 10 from each other and also a connecting strap would be used to afford an electric connection between each movable contact such as 6 and an adjacent fixed contact such as 13 such as is shown clearly in the above Prince patent, for example. Connecting rod 11 and operating rod 17 are suitably interconnected by a linkage mechanism generally indicated by the numeral 18 so that vertical movement of rod 17 causes horizontal movement of rod 11. The contacts 6 through 10 are moved to the open position by causing the operating rod 17 to move upwardly as by releasing a latch mechanism, not shown, so as to permit suitable contact opening springs, also not shown, to move the rod 17 upwardly.

For the purpose of causing the high dielectric arc extinguishing liquid, which occupies the space within the interrupter to the level indicated, to blast across the space between the interrupting contacts, a piston means generally indicated at 19 is provided. As is disclosed in the above Prince patent, piston 19 is operable in response to operation of operating rod 17 to cause a blast of arc extinguishing liquid to circulate from the enclosing housing 3 into the interrupting unit 5 in the direction indicated by the arrows through the gate valve 20, between the interrupting contacts, and back into the housing 3. As disclosed in the above Prince patent, a baffle board containing expulsion ports adjacent each pair of interrupting contacts could be utilized to facilitate the arc extinguishing blast action of the fluid. The piston 19 would be arranged with suitable check valves which would allow the fluid to flow from above the piston 19 to the space below the piston to permit circulation of the oil in the direction shown by the arrows and thereby to cause fresh oil to be available in the region of the contacts for each successive interrupting operation.

As may be observed from Fig. 1, the interrupting structure 5 comprises an inner tubular insulating casing 21 about which a plurality of ceramic insulating shells 22 are mounted. The insulating tube 21 is secured to the housing structure 3 by means of a metallic flange member 23 which is bolted to a wall of the structure 3 by the bolts 24. As is shown in Fig. 1 the outer periphery of tubular insulating casing 21 is provided at its ends with an annular groove which cooperates with the wedge-like inner periphery of the split ring-like member 23. The right-hand end of tubular casing 21 fits into and is supported by a suitable adapter such, for example, as the tubular member 25 which, in turn, is secured to the terminal cap 4.

The tubular casing 21 is surrounded by a plu-

rality of ceramic shell members 22 which are concentrically disposed with respect to the tubular casing 21. Associated with each end of each of the shell sections 22 is a supporting metal annulus 26. These supporting members 26 are secured to the end flanges of the ceramic shell sections 22 by any suitable means such as by the bolts 27. The inner periphery of each annular member 26 beds upon a flexible or resilient ringlike member 28 mounted snugly about the casing 21. Thus, it will be seen that the weight of the ceramic shells 22 is supported by the casing 21 through the annular supporting members 26 and the resilient rings 28. Slight bending of the casing 21 due to the heavy weight of the ceramic shell sections 22 is accommodated since the brittle shell sections together form an articulated shell enclosing the casing 21. In this way radial shocks due to vertical motion at either end caused by ground shock or reaction to motion of the vertical operating rod and other vertically moving parts as examples, are effectively absorbed by the resilient rings 28 and hence are not transmitted to the shell sections 22.

For the purpose of preventing the transmission of shocks longitudinally through the ceramic shell sections 22, I provide a plurality of ring-like resilient members 29 which allow limited cushioned axial motion by one or any of the ceramic shells 22 with respect to an adjacent shell, or with respect to either end structure. Thus, a shock from a source outside the interrupter such, for example, as a ground tremor, reaction to oil flow and other causes will not be likely to cause breakage of the shells 22, and furthermore the overall length of the interrupter unit 5 can be increased to any desired value within the limits imposed by the ability of the casing 21 to withstand bending stress.

The overall insulating properties of the interrupting unit 5 are improved if the space between the insulating tube 21 and the ceramic shells 22 is filled with a suitable dielectric such as oil, for example. In order to insure that this insulating oil will be evenly distributed throughout the length of the interrupting unit 5 at all times, I provide suitable communicating ports such as 30 disposed through the annular supporting members 26. At least one port such as 30 should be located at the top portion of the supporting members 26 to bleed air from the porcelain shells and at least one port 30 should be disposed at the bottom to facilitate oil drainage and to insure that the level of the insulating oil will be equalized through the length of the interrupter. Fluid is maintained within the space between casing 21 and the shells 22 from a suitable gravity reservoir such as 31 which communicates with the interrupter unit through the passageway 32. In order to seal adjacent surfaces of the annular supporting members 26, the metal Sylphon bellows 33 are brazed or welded between each adjacent pair to constitute a convenient manufacturing unit. The end bellows 34 forms a similar seal between the terminal cap 4 and the adjacent annular member 26 while the other end bellows 35 forms a seal between the wall of the housing 3 and the adjacent annular supporting member 26.

In view of the above description, it is clear that the whole shell comprises an articulated weather protecting cover member whose load is distributed uniformly along the back bone constituted by the interrupter casing and that by the invention, it is possible to increase the voltage rating of interrupters and at the same time

to provide an insulating structure which is relatively free of the harmful effects caused by vibration and shocks from whatever cause.

It will be understood that my invention is not limited to the specific details of construction and arrangement thereof herein illustrated, and that changes and modifications may be made without departing from the spirit and scope of my invention.

What I claim as new and desire to secure by Letters Patent of the United States is:

1. Enclosing structure for a high voltage electrical device comprising a firmly supported horizontally disposed hollow casing member of insulating material, a plurality of ceramic shell sections disposed in spaced relation about said casing member, an inwardly projecting metallic flange secured to each end of each shell section, a plurality of annular members of flexible material disposed on said casing and operably related with the inner surfaces of said flanges to form an articulated shell around said casing thereby to accommodate bending of said casing and to prevent the transmission of shocks to said shells, yieldable bellows means interposed between opposed surfaces of adjacent flanges and secured thereto to render said shell fluid tight, liquid dielectric material in said shell completely surrounding said casing, a first port disposed in a lower portion of each of said flanges for aiding in equalizing the level of said liquid surrounding said casing, and a second port in each of said flanges above the normal level of said liquid to prevent the accumulation of localized excessive pressures along the length of said shell thereby to facilitate the liquid level equalizing action of said first ports.

2. Enclosing structure for a high voltage electrical device comprising a firmly supported horizontally disposed semi-rigid hollow casing member of insulating material, a plurality of ceramic shell sections disposed in spaced relation about said casing member, an inwardly projecting metallic flange secured to each end of each shell section, an annular member of flexible material interposed between said casing and the inner surfaces of each of said flanges, resilient means interposed between adjacent opposed surfaces of some of said flanges to cushion said sections against longitudinal movement, said shell sections forming an articulated shell around said casing thereby to accommodate bending of said casing, yieldable bellows means interposed between opposed surfaces of adjacent flanges and secured thereto to render said shell fluid tight, liquid dielectric material in said shell completely surrounding said casing, and means including an opening in some of said flanges for maintaining a substantially constant level of fluid throughout the length of said shell.
